9 Claims. (Cl. 66—164)

1

This invention relates to circular knitting machines and more especially to an improved stop motion adapted to be associated with a wrap stripe attachment on a circular knitting machine of the type known as the Scott and Williams H. H. or PW machine.

In circular knitting machines of the type described, there is provided a rotating wrap head having a plurality of wrap fingers thereon which are adapted to move adjacent the needle cylinder at predetermined intervals to wrap a wrap thread around certain needles for producing wrap stripes in a knitted article. This rotating head moves in timed relation to the needle cylinder and has a plurality of circularly spaced stobs thereon, each of which supports a tube having wrap yarn thereon and which yarn is drawn from the tube upwardly through conventional tension apparatus and is then directed to the conventional wrap fingers. This conventional tension means usually has associated therewith a mechanism for stopping the knitting machine in the event any of the strands of the yarns are parted in their path from the tube of yarn to the corresponding wrap finger.

However, upon all of the yarn being withdrawn from any one of the tubes, the tension means would be relaxed and would again stop the machine, and in this event, the yarn frequently is withdrawn from the conventional tension means with the result that the yarn would have to be rethreaded through the tension means upon replacing the empty tube with a filled tube of yarn.

Although, some attempts have been made to provide a stop motion control for stopping the knitting machine upon the yarn from a tube being exhausted and prior to the yarn being drawn through the tension means, such means have required a considerable number of parts and one particular type of such means has required that the tube be provided with an opening in one side thereof to permit the extension of an arm therethrough, upon the yarn being exhausted from the tube or bobbin, for actuating the conventional stop motion of the knitting machine. Also, in using means heretofore provided to operate the stop motion of a knitting machine upon the yarn being exhausted from the bobbins or tubes, it would often happen that the yarns would still be partially withdrawn through the tension means before the knitting machine had stopped.

It is, therefore, an object of this invention to provide an improved stop motion for the wrap head of a knitting machine comprising

2

clamping means in the form of a thread clamp pivotally supported on the table of the wrap head immediately adjacent each of the stobs which support the packages or tubes of yarn and to which the tail of the yarn is clampingly connected. This pivoted clamping means has stop means associated therewith which is automatically released upon the last few turns of yarn on the corresponding tube being withdrawn therefrom and which causes the clamping means to be pivoted or elevated by the pull of the yarn with the result that the stop means is released to engage a suitable mechanism for actuating the stop motion of the knitting machine.

15 There are two forms of the invention shown in the drawings, the pivoted clamping means of the original form of the invention being pivotally supported in a block having a projection thereon and which is secured in the table or 20 plate of the wrap head by any suitable means, such as a pressed fit. In the modified form of the invention, the stob which is threadably embedded in the table of the wrap head has a shoulder thereon which clampingly secures a 25 support for the pivoted yarn clamp to the table, this support also containing the means for actuating the stop motion of the knitting machine, upon being released by the yarn clamping means. In using the modified or second form of the 30 invention, it is not necessary to drill holes in the table for the reception of the releasable means for actuating the conventional stop motion of the knitting machine or otherwise modify the conventional knitting machine.

35 Some of the objects of the invention having been stated, other objects will appear as the description proceeds when taken in connection with the accompanying drawings in which—

40 Figure 1 is an elevation of the upper part of a wrap stripe section of a circular knitting machine with portions omitted and broken away and showing the improved wrap yarn control stop motion actuating means in association therewith;

45 Figure 2 is an enlarged vertical sectional view taken substantially along the line 2—2 in Figure 1 and showing the means for effecting operation of the conventional stop motion of a knitting machine upon the improved stop motion actuating means being rendered operable;

50 Figure 3 is an enlarged fragmentary plan view looking down substantially along the line 3—3 in Figure 1 and showing the original form of the invention with one unit thereof in operative

55

position, the remaining units being shown in inoperative position and the tubes of yarn being omitted for purposes of clarity;

Figure 4 is a side elevation of the intermediate means for effecting operation of the conventional stop motion of the knitting machine responsive to the releasable actuating means of the present invention;

Figure 5 is a vertical sectional view taken substantially along the line 5—5 in Figure 4;

Figure 6 is an enlarged fragmentary vertical sectional view taken substantially along the line 6—6 in Figure 3 and showing the releasable actuating plunger in operative position to which position it is moved by centrifugal force upon being released through movement of the yarn clamping means;

Figure 7 is a fragmentary vertical sectional view taken substantially along the line 7—7 in Figure 6 but showing the plunger in an inoperative position;

Figure 8 is a fragmentary vertical sectional view along the line 8—8 in Figure 6 and showing the manner in which the restricted threaded portion of the stob or yarn tube holder limits outward movement of the corresponding stop motion actuating plunger;

Figure 9 is a fragmentary elevation looking substantially along the line 9—9 in Figure 3 and showing the yarn clamping means in elevated or operative position, in which position it is disposed upon the yarn from the cone or tube being exhausted;

Figure 10 is a fragmentary top plan view similar to Figure 3 but showing a modified or second form of the invention associated therewith;

Figure 11 is an enlarged fragmentary vertical sectional view taken substantially along the line 11—11 in Figure 10;

Figure 12 is an enlarged fragmentary vertical sectional view taken substantially along the line 12—12 in Figure 10;

Figure 13 is a fragmentary elevation with parts in section taken substantially along the line 13—13 in Figure 10 and showing the yarn clamping means in an elevated or operative position, this view being similar to Figure 9.

Referring more specifically to the drawings, the numeral 10 broadly designates a bracket rising upwardly from the body portion of a knitting machine of the type described and which has leg portions 11 and 12 which support a platform 13. On this bracket 10 is rotatably mounted a housing 14 having on the lower end thereof a plurality of radially movable wrap yarn fingers 15 which are adapted to be moved by certain mechanisms, not shown, but fully shown in Patents No. 1,853,020 or No. 1,906,204.

These radially movable wrap yarn fingers are provided for the well known purpose of depositing the wrap yarn across the needle cylinder to wrap the same around certain needles indicated at 16. The housing 14 is mounted for rotation and is driven by suitable means engaging the gear 17 disposed on the upper end thereof.

The housing 14 has a lower table 20 provided with a plurality of cone holders, tube holders or stops 21 which are shown in Figures 6 and 8, and each of which is provided with a reduced threaded portion 22 on the lower end thereof suitably embedded in the table 20. These stobs 21 are arranged in a circle on the table 20 and in spaced relation to each other.

The housing 14 also has an upper table 23 provided with a plurality of brackets 24 suitably se-

cured around the periphery thereof, only two of which are shown in the drawings. Each of the brackets 24 has pivotally mounted therein a yarn tension take-up lever 25 having a hook in its free end over which the wrap yarn W is adapted to be passed. The outer end of each of the tension levers 25 has a hook portion adapted to be hooked into an upwardly projecting member 26 secured to a tension disk 27 slidably mounted on a post 30 and is normally urged downwardly by a compression spring 31 surrounding said post, the tension in the compression spring being adjusted by a suitable thumb nut 32.

A fixed tension disk 33 is suitably secured to each of the brackets 24 and against which the movable tension disk 27 is urged by the spring 31. The tension levers 25 and the associated parts heretofore described may be of the type substantially as shown in United States Patent No. 2,430,633 of November 11, 1947, and also include a member pivoted in each of the brackets 24 and having an outwardly and upwardly projecting portion 38 and an inwardly and downwardly projecting hooked portion or member 39.

Each of the stobs or cone holders 21 is adapted to support a suitable cone or tube of wrap yarn indicated at 40. Wrap yarn passes upwardly from each of the cones 40 and between the corresponding two tension disks 27 and 33 and through a suitable opening in the bracket 24 and through the hook member 39 and then beneath a ring 42 secured on suitable uprising posts 43 rising from the table 23. Then the wrap yarn W passes through the hook on the free end of each of the corresponding levers 25 and extends downwardly through suitable tubes or conduits 44 which extend through the housing 14 and only the lower ends of which are visible in Figure 1. The wrap yarn then extends from the lower ends of the tubes 44 to the corresponding wrap yarn fingers 15. Each of the yarn tension levers 25 is normally urged upwardly against the tension of the yarn W by means of a tension spring 45 connected thereto and having its upper end connected to a spring anchor 46 secured on the corresponding bracket 24. The parts heretofore described are usual parts of a knitting machine of the type described having a wrap stripe mechanism associated therewith and it is with these parts that the present invention is adapted to be associated. It is evident, however, that there are many other types of yarn tension devices and stop motion actuating mechanisms which may be mounted on the upper table 23 to perform the functions of the apparatus heretofore described, the particular apparatus described being shown by way of illustration only.

During operation of the machine, upon the wrap yarn being severed on either side of the yarn tension apparatus of which the tension levers 25 are a part, it is evident that the member 39 will swing upwardly resulting in the outer portion 38 thereof being swung to assume substantially a horizontal position. Suitable means, not shown in the present drawings but being clearly shown in the United States Patents Nos. 2,430,633 and 2,472,649 are usually provided which are engageable by the portion 38 of the member 39 for actuating the conventional stop motion of the machine, this stop motion being of the type such as is shown in United States Patent No. 2,389,683.

The original or first form of the invention is shown in Figures 1, 3, 6, 7, 8 and 9 and comprises a vertically movable yarn tail clamp broad-

ly designated at 50 in the form of a pivoted member which may also be termed a pivoted latch. The yarn tail clamp 50 has an outwardly projecting tail portion or blade 51 which is rounded at the free end thereof, as at 52, so that the tail of the yarn W (Figure 9) may be slid along the portion 52 against the upper surface of the blade 51 be clampingly engaged by a leaf spring member 53 suitably secured at its end remote from the free end of the blade 51 to a second portion 54 of the blade 51. The leaf spring member 53 may be secured at one end thereof to the blade 51 as by riveting, soldering or in any other desired manner.

The yarn tail clamping member 50 has an upturned portion or projection 55 thereon which is integral with the enlarged or second portion 54 and which is bent outwardly to form a lip 56. This lip 56 is disposed in the bifurcated upper end of a yoke member or pivot block 57 and is pivotally mounted therein, as at 60. The yoke block 57 has a reduced portion 61, preferably circular in cross-section, extending downwardly therefrom and which is secured in the lower table 20 by any suitable means, such as a pressed fit.

A latch projection 62 extends from the lower surface of the blade 51 of the yarn tail clamping member 50 and is flattened at one side thereof and at an angle, as at 63, for purposes to be later described. When the latch is in a lowered or inoperative position, the projection 62 thereon enters a corresponding cavity 64 in the table 20, the walls of this cavity being tapered, as at 65, at the upper edge so as to tend to lead the projection 62 thereinto as the yarn tail clamping member 50 is lowered, by gravity, into engagement with the upper surface of the table 20.

Now, the table 20 is provided with a plurality of radially extending bores 68, there being one of these bores associated with each of the stobs 21 and as is most clearly shown in Figures 6, 7 and 8. These bores 68 are so positioned that upon the reduced threaded end 22 of the stob 21 being embedded in the table 20, the reduced portion 22 of the stob 21 will be partially disposed within the radially extending bore 68. Mounted for radial sliding movement in each of the bores 68 is a stop motion actuating plunger 69 which is flattened intermediate its ends, as at 70, for a part of the length of the plunger 69 and this flattened portion 70 engages the adjacent edge of the reduced portion 22 of the stob 21 thus preventing rotation of the plunger 69 in the bore 68 and also limiting inward and outward movement of the plunger 69.

The plunger 69 is preferably loosely mounted in the corresponding bore 68 so that centrifugal force transmitted to the plunger 69 through rotation of the table 20 will tend to throw the plunger 69 out of the bore 68 and, in which instance, the flattened portion 70 on the plunger 69, through engagement with the reduced threaded portion 22 of the corresponding stob 21, limits outward movement of the plunger 69.

The plunger 69 has an angularly extending notch 71 therein, the angularity of which is such as to coincide with the angularity of the surface 63 on the latch projection 62. The width of the notch 71 is such that the latch projection 62 will loosely fit within the confines of the notch 71 when the plunger assumes a position where the outer end thereof is flush with the peripheral edge of the table 20.

In operation, as each tube of yarn 40 is placed

on a corresponding one of the stobs or yarn tube holders 21, the tail of the yarn, that is, the end of the yarn which will last be removed from the tube 40, is inserted between the leaf spring member 53 and the blade 51 of the yarn tail clamping member 50 while the yarn tail clamping member 50 is in a horizontal lowered or inoperative position and the latch projection 62 thereof is projecting into the cavity 64 and is in engagement with the notch 71 in the corresponding plunger 69.

Now, during normal operation of the wrap stripe mechanism upon the severage of any of the yarns from the corresponding tube 40, the conventional tension apparatus, of which the tension lever 25 is a part, will operate to stop the knitting machine in a conventional manner. However, in order that the tension in the yarn W need not necessarily be relaxed in order to stop the machine upon the yarn on any one of the bobbins or tubes 40 being exhausted and to thereby prevent the yarn from being drawn through the tension apparatus which would normally necessitate its being rethreaded there-through upon the installation of a succeeding tube of yarn, the clamping means 50 is provided. Upon the yarn of the corresponding tube 40 being exhausted, the clamping means 50 will be raised from substantially the position shown in Figures 1, 6 and 7 to the position shown in Figure 9. It is evident that this will release the plunger 71 from the latch projection 62 on the corresponding yarn tail clamping member 50 and the plunger 69 will then be thrown outwardly to assume substantially the position shown in Figure 6 and with the result that the plunger will be so positioned as to engage a suitable means for effecting operation of the conventional stop motion of the loom such as the belt shifting apparatus shown in the United States Patent No. 2,389,688.

In the present instance, there is provided an improved intermediate stop motion actuating means broadly designated at 80 which comprises a plate 81 suitably secured to the platform 13, as by screws 82. This intermediate stop motion actuating means includes an arm 83 which is mounted in a manner to be presently described, so as to be moved by the plunger 69 which is projected outwardly relative to the periphery of the table 20 which thus causes a Bowden wire 84 to move in a predetermined direction for operating the conventional stop motion of the knitting machine.

The novel intermediate means 80 for effecting operation of the conventional stop motion of the knitting machine upon any one of the actuating plungers 69 being thrown partially out of the corresponding bore 68 also has a tubular member 85 suitably secured thereto, as by screws 86 and 87 (Figure 2) and this tubular member has a restricted end portion 90 integral therewith in which a piston rod or auxiliary plunger 91 has longitudinal sliding movement.

For resetting purposes, the outer end of the auxiliary plunger 91 has a cap member 92 suitably secured thereon, as by being threadably mounted thereon and which is engageable by an operator for pushing the auxiliary plunger 91 inwardly or from right to left in Figure 2 for purposes to be later described.

The auxiliary plunger 91 has an enlarged piston portion 93 integral therewith which is mounted for longitudinal sliding movement in the tubu-

lar member 85 and the left-hand end thereof in Figure 2 is engaged by a compression spring 94. The other end of the compression spring 94 engages a stop member 95 which is fixedly secured in the tubular member 85 adjacent the left-hand end thereof in Figure 2 as by a screw 87 penetrating the wall of the tubular member 85 and bearing against the stop member 95. This stop member 95 is slidably penetrated by the plunger 91, the enlarged piston portion 93 being disposed intermediate the ends of the plunger 91. The end of the auxiliary plunger 91 remote from the end to which the head member 92 is connected is reduced, as at 96, for the reception of the Bowden wire 84 heretofore described. The housing of the Bowden wire 84 is clampingly secured in a clamping member 97 which is suitably secured, as by a screw 98, to the upper surface of the plate 81.

It will be observed in Figure 3 that one end of a stud 100 is fixedly secured, as by a pressed fit, in the tubular member 85 and extends outwardly from one side thereof. This stud 100 has one end of a detent support plate 101 loosely mounted thereon, this plate 101 extending in parallel relation to the tubular member 85. A compression spring 102 surrounds the stud 100 and urges the plate 101 against the tubular member 85 at the stud 100. A pair of lock nuts 103 are threadably mounted on the stud 100 which serve to confine the spring 102 thereon and also support a leaf spring member 104 therebetween. This leaf spring member 104 extends outwardly from the stud 100 and its free end bears against the medial portion of the plate 101 to normally urge the end of the plate 101 remote from the stud 100 against the tubular member 85. The tubular member 85 has a passageway or bore 105 therein and a detent in the form of a screw 106 threadably penetrates the plate 101 and loosely or slidably penetrates the bore 105.

This screw 106 is locked in the desired adjusted position by a lock nut 107 threadably mounted thereon and is so positioned that the free end thereof will slidably engage the piston rod or auxiliary plunger 91. The spring 94 (Figure 2) normally urges the enlarged piston portion 93 of the auxiliary plunger 91 against the detent 105.

Now, referring to Figures 2 and 3, it will be observed that the tubular member 85 has a shoulder screw 110 threadably embedded in the upper surface thereof on which a cam 111 is oscillatably mounted, this cam 111 being shown as substantially octangular in Figure 3. The finger 83 heretofore described, which is adapted to be engaged by any one of the stop motion actuating plungers 69 which may have been released by the latch member 50, is threadably embedded in the cam member 111 and extends radially therefrom.

In operation, the cam 111 is normally disposed in the position shown in Figure 3. However, upon the free end of the finger 83 being engaged by any one of the plungers 69, rotation will be imparted to the cam 111 causing the same to move the detent plate 111 outwardly and, of course, this will cause the detent 106 to move out of engagement with the enlarged portion 93 of the auxiliary plunger 91 thus permitting the compression spring 94 to move the plunger 91 from left to right in Figures 2 and 4 or downwardly in Figure 3. It is evident that this would cause the Bowden wire 84 to move in a like direction to thus actuate the conventional stop motion, not shown, which is clearly shown in said Ruth Patent No. 2,389,688 and the Fogleman, et al. Patent No. 2,430,633. A new bobbin may then be placed on the stob 21 and the yarn thereon may be con-

nected to the tail of the yarn W and it will not be necessary to rethread the yarn.

Due to the fact that the framework of many knitting machines varies, the intermediate stop motion actuating device 80 may be placed in a different position relative to the table 20 and, therefore, the cam 111 is so formed that it may be moved in either direction and will still move the detent 106 out of engagement with the enlarged portion 93 of the auxiliary plunger 91 (Figure 2).

It is evident that upon the knitting machine being stopped in the manner heretofore described, the bobbin or cone of yarn 40 may be replaced and the corresponding plunger 69 may be moved inwardly so that its outer ends are flush with the periphery of the table 20. Also, it is necessary that the auxiliary or intermediate stop motion actuating device 80 be reset so as to be conditioned for a repeat operation. In this event, it is merely necessary for an operator to press the member 92 to cause movement of the plunger 91 inwardly or from right to left in the tubular member 85 (Figure 2) until the enlarged portion 93 has moved beyond the detent 106. The detent 106 will then move into operative position so that upon releasing the plunger 92, the detent 106 will again engage the right-hand end of the enlarged portion 93 of the auxiliary plunger 91 under pressure of the compression spring 94.

Second or modified form

Referring to Figures 10, 11, 12 and 13, there is shown a second or modified form of the invention which functions in substantially the same manner as the original form of the invention shown in Figures 1 to 9. However, in using the modified form of the invention, it is not necessary to drill holes in the table 20 since the modified form of the invention is clampingly secured to the table by the conventional stobs 21.

Since the conventional parts of a knitting machine are identical in both forms of the invention, the same reference characters will apply, and, also, since the intermediate or auxiliary stop motion actuating unit 80 is also employed in association with the modified form of the invention, without any modifications thereof, the same reference characters will also apply to this device 80 in association with the modified form of the invention.

The modified form of centrifugally operable stop motion actuating device comprises a bracket or support broadly designated at 120 which, for purposes of simplicity of manufacture, is shown as being formed of sheet metal. It is to be understood however that the bracket 120 may be machined of a solid piece of material or cast or made in any other desired manner and of any desired workable material. The bracket 120 comprises a planar portion 121 which is relatively thin and which has an adjustment slot 122 therein which is adapted to be penetrated by the reduced portion 22 of the corresponding stob or yarn cone holder 21. The shoulder formed at the juncture of the reduced threaded portion 22 and the enlarged portion of the stob 21 clampingly secures the plate 121 of the bracket 120 to the upper surface of the table 20.

The plate 121 has a tubular portion 123 formed therein in which an enlarged portion 124 of a centrifugally operable stop motion actuating plunger 125 is mounted for longitudinal sliding movement, this plunger 125 being adapted to move substantially along a radius of the table 20.

This plunger 125 also has a reduced outer end portion 126 integral therewith which slidably penetrates an upturned lip portion 127 integral with the plate or base portion 121.

A latch or yarn tail clamping member broadly designated at 130 is pivotally mounted on opposed ends of a pivot pin 131 which extends through the tubular portion 123 of the bracket 120 and serves to restrict movement of the plunger 125 towards the axis of the table 20. This yarn tail clamping member 130 has a longitudinally extending blade portion 132 integral therewith to the upper surface of which a leaf spring clamping member 133 is suitably secured, as by rivets 134. It will be noted that the free end of the leaf spring member 133 is turned upwardly or away from the blade 132, as at 135, to facilitate the ingress of a thread yarn tail between the blade 132 and the leaf spring member 133 to be secured thereby.

The medial portion of the blade 132 has a down-turned latch portion 136 integral therewith which is adapted to engage the outer end of the enlarged portion 124 of the plunger 125 at its juncture with the reduced portion 126. The tubular portion 123 of the bracket 120 has an opening or passageway 137 which is loosely penetrated by the projection 136 when the blade 132 of the clamping member 130 assumes a horizontal or inoperative position. However, upon the yarn being substantially exhausted from the associated cone or tube 40, the upward pull of the yarn W will cause the yarn clamping member 130 to swing upwardly substantially as shown in Figure 13 and, due to rotation of the table 20, centrifugal force will cause the reduced portion 126 of the plunger 125 to move outwardly to occupy substantially the position shown in Figure 13, outward movement thereof being limited through engagement of the enlarged portion 124 with the proximate surface of the upturned portion 127 of the bracket 120.

It is evident, that, upon the reduced portion 126 of the plunger 125 being thrown outwardly through centrifugal force, it will engage the finger 83 of the corresponding intermediate or auxiliary stop motion actuating device 80 to cause the same to operate in the manner heretofore described for stopping the knitting machine.

It is thus seen that I have provided an improved means for effecting operation of the conventional stop motion of a knitting machine upon the yarn from any one of the tubes 40 being exhausted and which includes means for clampingly holding the yarn to prevent the same from being withdrawn through the conventional tension devices such as the tension levers 25. This, of course, saves considerable time in the replacing of empty tubes 40 with filled tubes of yarn as well as providing a positively actuated means for stopping the knitting machine upon the exhaustion of yarn from any one of the tubes 40.

The present apparatus is also relatively simple in construction and thus may be economically manufactured and requires a minimum of modifications of the existing parts of the knitting machine. As a matter of fact, the second form of the invention shown in Figures 10, 11, 12 and 13 does not require any modification whatsoever to be made in the knitting machine.

In the drawings and specification there has been set forth a preferred embodiment of the invention and although specific terms are employed, they are used in a generic and descriptive

sense only and not for purposes of limitation, the scope of the invention being defined in the claims.

I claim:

- 5 1. In a knitting machine having a revolving wrap stripe mechanism including a rotatable table supported by the revolving wrap stripe mechanism, said table having mounted on the upper side thereof a plurality of upstanding circularly spaced stops for holding yarn cones filled with wrap yarn, a vertically movable yarn clamping means disposed adjacent each of said stops and adapted to secure the tail of the yarn on the corresponding cone, a movable plunger carried by the table in association with each of said yarn clamping means, means on the yarn clamping means for normally preventing movement of the corresponding plunger, stop motion actuating mechanism located adjacent the revolving wrap stripe mechanism and means on the stop motion actuating mechanism engageable by said plungers upon the plungers moving outwardly from said table and means on said clamping means causing the plunger associated therewith to move outwardly from said table upon substantial exhaustion of the yarn from one of the yarn cones.
- 10 2. In a knitting machine having a revolving wrap stripe mechanism including a rotatable table having a plurality of circularly spaced stops thereon for holding yarn cones filled with wrap yarn, movable yarn clamping means associated with each of said stops for clamping the tails of yarn on said cone, a movable plunger carried by said rotatable table in association with each of said movable yarn clamping means, said yarn clamping means having means thereon normally preventing movement of the corresponding plunger, exhaustion of the yarn from any of said cones causing movement of said corresponding movable yarn clamping means to release said corresponding plunger, said plunger being adapted to move outwardly from said table by centrifugal force upon release thereof, intermediate stop motion actuating mechanism disposed adjacent the revolving wrap stripe mechanism and said plungers being adapted to actuate said intermediate stop motion actuating mechanism to stop the knitting machine upon exhaustion of yarn from one of said cones.
- 15 3. In a knitting machine having a stop motion and having wrap stripe means for holding a plurality of cones of wrap stripe yarn thereon, the member for holding the cones being adapted to be revolved in time relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction
- 20 4. In a knitting machine having a stop motion and having wrap stripe means for holding a plurality of cones of wrap stripe yarn thereon, the member for holding the cones being adapted to be revolved in time relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction
- 25 5. In a knitting machine having a stop motion and having wrap stripe means for holding a plurality of cones of wrap stripe yarn thereon, the member for holding the cones being adapted to be revolved in time relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction
- 30 6. In a knitting machine having a stop motion and having wrap stripe means for holding a plurality of cones of wrap stripe yarn thereon, the member for holding the cones being adapted to be revolved in time relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction
- 35 7. In a knitting machine having a stop motion and having wrap stripe means for holding a plurality of cones of wrap stripe yarn thereon, the member for holding the cones being adapted to be revolved in time relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction
- 40 8. In a knitting machine having a stop motion and having wrap stripe means for holding a plurality of cones of wrap stripe yarn thereon, the member for holding the cones being adapted to be revolved in time relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction
- 45 9. In a knitting machine having a stop motion and having wrap stripe means for holding a plurality of cones of wrap stripe yarn thereon, the member for holding the cones being adapted to be revolved in time relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction
- 50 10. In a knitting machine having a stop motion and having wrap stripe means for holding a plurality of cones of wrap stripe yarn thereon, the member for holding the cones being adapted to be revolved in time relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction
- 55 11. In a knitting machine having a stop motion and having wrap stripe means for holding a plurality of cones of wrap stripe yarn thereon, the member for holding the cones being adapted to be revolved in time relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction
- 60 12. In a knitting machine having a stop motion and having wrap stripe means for holding a plurality of cones of wrap stripe yarn thereon, the member for holding the cones being adapted to be revolved in time relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction
- 65 13. In a knitting machine having a stop motion and having wrap stripe means for holding a plurality of cones of wrap stripe yarn thereon, the member for holding the cones being adapted to be revolved in time relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction
- 70 14. In a knitting machine having a stop motion and having wrap stripe means for holding a plurality of cones of wrap stripe yarn thereon, the member for holding the cones being adapted to be revolved in time relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction

4. In a knitting machine having a stop motion and having wrap stripe means for holding a plurality of cones of wrap stripe yarn thereon, the means for holding the cones being adapted to be revolved in timed relation to the cylinder of the knitting machine, said machine also having means for holding said cones, centrifugally operable means for effecting operation of the stop motion comprising a movable plunger disposed adjacent each of the means for holding the cones, a pivoted latch member disposed adjacent each of the means for holding the cones and having means thereon normally limiting movement of the corresponding plunger, means on the pivoted latch member for securing a tail of yarn from the corresponding cone of yarn thereto, whereby upon the yarn being exhausted from any one of said cones, the tail thereof will cause the pivoted latch member to swing in one direction for releasing the corresponding plunger, rotation of the means for holding the plurality of cones causing said plunger to be moved away therefrom, means engageable by said plunger for effecting operation of the stop motion, said pivoted latch member including a pivoted arm, means pivotally supporting the pivoted arm on the table, a leaf spring member secured at one end thereof to the pivoted arm and normally bearing against the pivoted arm whereby a tail from the associated cone of yarn may be inserted between the leaf spring member in said arm for clampingly securing the same thereto.

5. In a circular knitting machine having a wrap stripe head including a rotary table provided with a plurality of spaced yarn cone holders thereon for holding cones of wrap yarn, said knitting machine also having a stop motion, means for actuating said stop motion upon the yarn in any one of said cones being exhausted comprising a yarn clamping member pivotally secured to said table adjacent each of said yarn cone holders, said yarn clamping members having means thereon for clamping tails of yarn from said cones therein, said table having a radially extending bore therein adjacent each of said yarn cone holders, a plunger slidably mounted in each of said bores, each of said yarn clamping members having latch means thereon adapted to hold said corresponding plunger within said bore upon a full cone of yarn being positioned on said yarn cone holder, exhaustion of the yarn on said yarn cone causing pivotal movement of said yarn clamping member to release said latch means to cause said plunger to move outwardly from said table by centrifugal force, intermediate stop motion actuating means engageable by said plungers upon outward movement thereof for actuating said stop motion of said knitting machine.

6. In a circular knitting machine having a wrap stripe head including a rotary table provided with a plurality of spaced yarn cone holders thereon for holding cones of wrap yarn, said knitting machine also having a stop motion, means for actuating said stop motion upon the yarn in any one of said cones being exhausted comprising a yarn clamping member pivotally secured to said table adjacent each of said yarn cone holders, said yarn clamping members having means thereon for clamping tails of yarn for said cones therein, said table having a radially extending bore therein adjacent each of said yarn cone holders, a plunger slidably mounted in each of said bores, each of said yarn clamping members having latch means thereon adapt-

ed to hold said corresponding plunger within said bore upon a full cone of yarn being positioned on said yarn cone holder, exhaustion of the yarn on said yarn cone causing pivotal movement of said yarn clamping member to release said latch means to cause said plunger to move outwardly from said table by centrifugal force, intermediate stop motion actuating means engageable by said plungers upon outward movement thereof for actuating said stop motion of said knitting machine, said intermediate stop motion actuating mechanism comprising an arm engageable by said plunger, a cam mounted on one end of said arm, a movable piston adapted to be actuated by said cam, and said piston having a wire secured thereto for actuating said stop motion.

7. In a circular knitting machine having a wrap stripe head including a rotary table provided with a plurality of spaced stobs thereon adapted to receive cones of wrap yarn, said knitting machine also having a stop motion for stopping the same, improved means for actuating said stop motion upon exhaustion of the wrap yarn from one of said wrap yarn cones comprising intermediate stop motion actuating means disposed on said machine adjacent the periphery of said wrap stripe head including a wire connected at one end to the stop motion, a cylinder having a movable piston therein, said wire being connected at its other end to the said piston, cam means for moving said piston, an arm connected to said cam means, said rotary table having means therein adapted to engage said arm for actuating said intermediate stop motion actuating means, and said means on the said rotary table comprising a movable plunger associated with each of said stobs, latch means normally holding said plunger out of engagement with said arm, said latch means having means thereon for clampingly engaging the tail end of the yarn on the associated cone, whereby exhaustion of the yarn on said cone will cause movement of said latch means to permit said plunger to engage said arm for actuating said stop motion.

8. In a circular knitting machine having a wrap stripe head including a rotary table provided with a plurality of spaced yarn cone holders thereon for holding cones of wrap yarn, said knitting machine also having a stop motion, a stop motion actuating mechanism disposed adjacent the periphery of the table, an improved stop motion control device comprising a bracket secured to the upper surface of said table adjacent each of said yarn cone holders and having a plunger mounted for movement therein, a pivoted clamping member pivotally connected to the bracket for clampingly engaging a tail of yarn from the corresponding cone, said pivoted clamping member having latch means thereon normally engaging said plunger to limit its outward movement from said table and actuating means on the stop motion actuating mechanism disposed immediately adjacent the periphery of said table, whereby, upon the yarn being substantially exhausted from an adjacent cone, the tail thereof will be pulled upwardly to swing the yarn clamping member in a like direction to cause the latch means thereof to release the plunger thereby permitting the plunger to move outwardly to engage said actuating means for the stop motion actuating mechanism for stopping the machine.

9. In a circular knitting machine having a wrap stripe head including a rotary table pro-

vided with a plurality of spaced yarn cone holders thereon for holding cones of wrap yarn, said knitting machine also having a stop motion adjacent the periphery of the table, an improved stop motion control device comprising a bracket secured to the upper surface of said table adjacent each of said yarn cone holders and having a plunger mounted for movement therein substantially radially of the axis of said table, a pivoted clamping member pivotally connected to the bracket and having means thereon for anchoring the tail of yarn from the corresponding cone thereto, said pivoted clamping member having latch means thereon normally engaging the plunger to limit its outward movement which may be imparted thereto by centrifugal force,

intermediate stop motion actuating mechanisms disposed immediately adjacent the periphery of said table and engageable by said plunger upon outward movement thereof, whereby, upon the 5 yarn being substantially exhausted from a cone, the tail thereof will be pulled upwardly to swing the yarn clamping member in a like direction to cause the latch means thereof to release the plunger thereby permitting centrifugal force to throw the plunger outwardly to engage said intermediate stop motion actuating means for stopping the machine.
